UNITED STATES PATENT OFFICE.

CHARLES P. KIMMEL, OF GARY, INDIANA.

RAIL-FASTENING DEVICE.

Application filed October 24, 1925. Serial No. 64,580.

To all whom it may concern:

Be it known that I, CHARLES P. KIMMEL, citizen of the United States, residing at Gary, Indiana, in the county of Lake and State of Indiana, have invented certain new and useful Improvements in Rail-Fastening Devices, of which the following is a specification.

My invention relates to clamping means for railroad rails and particularly to an improvement on the construction disclosed in the copending applications, Serial No. 23,192, filed April 15, 1925, and Serial No. 63,068, filed October 17, 1925.

An object in the present construction is to provide a simplified holding device adapted for use in connection with metal ties of the type disclosed in the copending applications referred to. The tie particularly contemplated is one of hollow, metallic form and provided with an open slot in its upper surface. In the improved form of my holding device, I provide a clamp having a head overlying the rail base, a body of tapered form, a foot adapted to enter a recess in the tie and a toe adapted to be distorted. The only other essential element is a key of generally I-shaped cross section, adapted for wedge engagement with the body of the clamp and further adapted to be held against escape by reason of the distorted toe of the clamp.

A clamp of the kind herein disclosed possesses numerous advantages due to the relative simplicity of the parts, there being but two of such parts constituting the clamp. Of course, I may see fit to construct the key in two parts to facilitate engagement with the tie, in which case there will be three parts. The form of the holding connection is such that the parts may be massive in construction, thus avoiding any possibility of displacement of the rail due to failure of the clamp. The holding connection is permanent and positive and yet the clamp may easily be disengaged for replacement of rails if desired.

The invention will be more readily understood by reference to the accompanying drawings, in which:

Fig. 1 is a plan view of a portion of a tie and rail with my improved fastening device associated therewith, one form of the fastening device in which the key is composed of two parts being shown in the right-hand portion of the view, and another form

in which the key is composed of one part being shown in the left hand part of the view;

Fig. 2 is a sectional view on the line 2—2 of Fig. 1;

Fig. 3 is a sectional view on the line 3—3 of Fig. 2;

Fig. 4 is a plan view of the clamp,

Fig. 5 is an end view thereof,

Fig. 6 is a perspective view of one half of the key shown in Fig. 3, and

Fig. 7 is a perspective view of the key composed of one piece instead of two.

In the drawings, it will be seen that the tie, 10, is of hollow form and is provided with a slot, 11 in the upper wall thereof, this slot extending from end to end of the tie. At a point on each side of the rail, 12, I provide notches, 13, in the slot for a purpose to be later described.

In the illustration, the rail is shown as resting on a tie plate, 14, of generally arcuate form. Where required, I will also provide suitable insulation for the rail.

The rail clamp comprises a head, 15, having a portion overlying the rail base, a neck, 16, and a body, 17, which as best shown in Fig. 4, is bifurcated, the upper surfaces, 18, of which bifurcated portions being inclined downwardly and outwardly. On the lower surface of each of the body portions, I provide a foot, 19, adapted to enter the notches, 13, in the tie and to abut against an outer wall thereof. Thus the clamp is held against lateral movement by positive engagement between metal parts, and the area of contact between such parts may be such as to positively prevent spreading of the rails.

The means for holding down the clamp consists of a key which may be of two parts, 20, 21, together constituting a member of generally I-shaped cross section; or the key may be composed of one piece as shown at 22 in Figures 1 and 7. In the latter case,

the key must, of necessity, be slid inwardly from the end of the tie. Where composed of two pieces, the key may be inserted at any point between the ends of the tie by first inserting one part, moving it to position and then inserting the complementary part and moving it into position. The key is provided with side recesses or slots, 23, the upper walls of which slots are angularly disposed as at 24, to provide an inclined surface adapted to contact with the inclined surface, 18, on the parts of the body. Thus

the key may be driven by means of a hammer or sledge into positive wedging engagement, the under walls, 25, of the side slots underlying the material adjacent to the open slot, 11, in the tie.

When suitably positioned, the key may be held in place by bending up the toe or extremity, 26, of the body, into the position shown in dotted lines, in Fig. 2. Thus the parts are firmly held in an immovable position without possibility of displacement except by distorting the metal.

If it becomes desirable to remove one or both of the clamps, a wedge or drift pin 27, shown in dotted lines in Fig. 2, may be inserted in the open space at the end of the key and the key may thus be driven off and the parts released; or the distorted toe may be driven down to its original position as a preliminary to the application of the displacing wedge.

It will be noted that the holding connection is extremely firm, rigid and unyielding; that the parts are of extreme simplicity and that the means employed adapt themselves to simple and economical labor operations in installation. I have illustrated but one of several modifications that might be made without departure from the spirit of my invention, and I do not wish to be limited except as indicated in the appended claims.

I claim:

1. In a rail fastening device, the combination with a slotted tie and a rail resting thereon, of a rail clamp having a portion overlying the rail base, a tapered portion and a toe, and a holding key engaging in the slot in the tie and having an inclined surface for engagement with the rail clamp, the toe of the rail clamp being adapted to be distorted to retain the key in holding position.

2. In combination with a slotted tie and a rail resting thereon, of a rail clamp having a head portion overlying the base of the rail, a tapered base portion and a bendable toe portion, and a key adapted to enter the slot in the tie and to overlie the base portion of the clamp and to be held against escape by distorting the toe portion of the clamp.

3. The combination with a slotted tie and a rail base, of a rail clamp having a portion overlying the rail base and a tapered portion lying alongside of the slot in the tie, and a fastening key underlying a portion of the tie, and overlying the base of the clamp, the extremity of the clamp being adapted to be distorted to hold the key in position.

4. The combination with a tie having a slot in its upper surface of a rail mounted on said tie, a rail clamp having a head overlying the base of the rail and having a tapered base portion terminating in a bendable toe, and a key entering the slot in the tie and having a portion overlying and fitting

the base of the clamp, said key being held in position by distorting the toe of the clamp.

5. In combination a tie having a recess in its upper surface, a rail, and a rail clamp having a portion entering the recess in the tie, and a key overlying the rail clamp, said key and clamp having correspondingly inclined surfaces whereby the key and the clamp are held in wedged relation, the extremities of the clamp being adapted to be bent over to retain the key in position.

6. The combination with a tie having an open slot in its upper surface and a rail resting thereon, of a clamp having a head overlying the base of the rail, a tapered body lying alongside of the slot in the tie and having a projecting toe to the tie and clamp having an inter-engaging recess and projection providing a fixed stop against lateral movement of the clamp, and a retaining key having a portion underlying the tie and a portion overlying the clamp, the projecting toe on the clamp being adapted to be distorted to act as a holding means.

7. In a rail holding device, the combination with a slotted tie and a rail, of a clamp having a head overlying the rail base, a tapered body lying alongside of the slot in the tie, a foot acting as a stop against lateral movement and a toe adapted to be distorted, and a key entering the slot in the tie and overlying the body of the clamp and having wedge engagement therewith, said key being held in place by distorting the toe of the clamp.

8. In a rail holding device, the combination with a slotted tie and a rail, of a rail clamp having a head overlying the rail base and a bifurcated body having a toe, the space between the two parts of the body corresponding to the slot in the tie, said body portion having a downward projection adapted to enter a recess in the tie and act as a lateral stop, and a key entering the slot in the tie and extending between the two parts of the body and overlying the upper surface thereof and adapted to be driven into wedge engagement therewith, the toe of the clamp being adapted to be distorted to retain the key in holding relation.

9. In combination, a tie having a recess in its upper surface, a rail, and a rail clamp having a portion entering the recess in the tie, and a key overlying the rail clamp, said key and clamp having correspondingly inclined surfaces whereby the key and the clamp are held in wedged relation, and positive means for preventing the key from backing off from its position.

10. In combination a tie having a recess in its upper surface, a rail and a rail clamp having a portion entering the recess in the tie, and a key overlying the rail clamp, said key and clamp having correspondingly in-

clined surfaces whereby the key and the clamp are held in wedged relation and means adapted to be distorted for holding the key against backward movement.

5 11. In combination a tie having a recess in its upper surface, a rail and a rail clamp having a portion entering the recess in the tie, and a key overlying the rail clamp, said key and clamp having correspondingly in-

clined surfaces whereby the key and the clamp are held in wedged relation, and means integral with the clamp adapted for distortion to hold the parts in operative relation.

In testimony whereof I have affixed my ¹⁵ signature.

CHARLES P. KIMMEL.
